DESK TELEPHONE SET

Hans Sengbusch, Villa Park, Ill., assignor to Associated Electric Laboratories, Inc., Chicago, Ill., a corporation of Delaware

Application September 17, 1938, Serial No. 230,366

4 Claims. (Cl. 179—148)

The invention relates in general to telephone sets but more particularly to an improved desk telephone of the cradle type.

An object of the invention is to improve the construction of the desk telephone shown and claimed in an application of Herbert F. Obergfell, Ser. No. 218,356, filed July 9, 1938, to facilitate moving the same by hand from place to place by providing pivoted fingers lifting ball which 5 is rotatable above the handset of the telephone for the purpose of lifting the entire telephone without displacing the hand telephone on the cradle.

Other objects and features of the invention 15 will be apparent from the detail description of the drawings comprising Figs. 1 to 7, inclusive.

Fig. 1 shows a perspective view of the preferred embodiment of the invention with the hand telephone removed from the cradle.

Fig. 2 shows a cross section with the hand telephone on the cradle and the fingers lifting ball in operated or lifting position. The dotted lines show the fingers lifting ball in normal position.

Figs. 3 and 4 show, respectively, front and side 25 views of the preferred fingers lifting ball.

Fig. 5 shows a front view of the mounting block in which the fingers lifting ball is rotatably mounted.

Figs. 6 and 7 show fingers lifting ball having a 30 slightly different shape.

Referring now in general to the drawings the cover 10 of the desk telephone is formed in one piece of some suitable plastic insulating compound and has a general shape roughly corresponding to a truncated pyramid thereby enabling ease in moulding. The base portion of the cover comprises ten sides or skirts 11 which extend substantially vertical for a short distance at which point the front, rear, and side surfaces 35 slope inwardly. The two side surfaces 12 and 13 slope upwardly and inwardly from the skirt side-portion only a short distance at which point both the side surfaces extend substantially vertical. The front surface 14 slopes upwardly and inwardly at an angle of substantially 40 degrees until it is rounded in a substantially horizontal top portion 15 which extends a short distance to the rear where it merges into the rear surface 16. The rear surface 16 extending from the rear 45 skirts 11 to where it merges with the top portion 15 slopes upwardly and inwardly. The slope of the rear surface 16 is a perfect arc of a circle having substantially a nine inch radius. The two side surfaces form side walls 17 and 18 which 50 extend from the top portion 15 near the front to

the rear skirts 11, thereby forming a channel comprising the two inside surfaces 19 and 20 of the side walls and the curved rear surface 16. Each side wall at its highest point terminates in a pair of spaced pillars 21. The space between 5 these pillars forming a cradle for the well-known combination transmitter and receiver handset.

A plunger 22 is movably mounted in the space between the two pillars in each side wall. These plungers are provided for operating the switch-hook springs (not shown) whenever the handset is removed or replaced on the cradle.

A base plate 23 having a rubber ring 24 is secured to the bottom of the cover by means of screws which screw into threaded inserts in the 15 cover.

The channel formed by the curved rear surface 16 and the inside surfaces 19 and 20 of the two side walls 17 and 18 starts at the rear and gradually deepens. Its greatest depth being at a vertical point from the two rear pillars 21 in the side walls. Due to the depth of the channel the fingers can firmly grasp the underside of a handset (not shown) resting on the plungers 22 in the cradle between the pillars 21 and side walls 17 25 and 18. In known desk sets only the tip ends of the fingers can grasp the sides of the handset resulting in an insecure finger grip on the handset. This insecure finger grip often permits the handset to fall after it has been removed from 30 the cradle. In case the handset slips and falls from the insecure finger tip grip considerable damage or breakage may occur.

Another advantage provided by this channel is to minimize cord interference. For example, 35 a subscriber, in hurriedly replacing the handset on the cradle, may allow the cord extending from the desk stand to the handset, to loop between the plungers of the cradle. In many instances these loops prevent the proper depression of the 40 plungers since the handset rests on the cord and does not depress the plungers sufficiently to properly control the substation circuit. Under these conditions the telephone is temporarily out of 45 service in regard to incoming calls. This defect has been overcome by providing a channel which starts near the front pillars and which has sufficient depth so that the cord will not interfere with the proper operation of the plungers in case the cord is accidentally looped in between the 50 pillars.

Mounting blocks 32 are provided between each pair of pillars 21 in the side walls 17 and 18. These mounting blocks 32 form the top surface 55 of the cradle which supports the hand telephone

and are provided with threaded screw holes 36 into which screws from inside the casing hold the mounting block in place. A hole 37 is provided in each mounting block 32 for the plungers 22 which operate the cradle switchhook springs (not shown). A hole 35 is also provided in each mounting block 32 for pivotally mounting the fingers lifting bail 50 or 70.

Due to the general shape of the cover or casing 10 which is provided with smooth sloping sides, the desk telephone is not easily picked up and moved by hand from place to place because no suitable finger or hand grip is available for lifting and moving the desk telephone. In order to provide means for easily lifting and moving the desk telephone from place to place a fingers lifting bail 50 has been provided. The lifting bail 50 is in general U-shaped. The open ends of this U-shaped lifting bail 50 are provided with rounded pins 51 which are insertable in the holes 35 of the mounting blocks 32 for the purpose of rotating the closed end or the finger grip end of the lifting ball above the hand telephone 60. The dotted lines in Fig. 2 show the lifting bail 50 resting in the channel between the side walls 17 and 18. In this position the bail 50 does not in any way interfere with fingers of the user when removing the hand telephone 60 from the cradle. The depth of the channel below the cradle is sufficient to allow the fingers of the user to grasp the underside of the hand telephone thereby providing a better grip of the hand telephone than is provided by most desk telephones which permit only the finger tips to grasp the sides of the hand telephone when removing the same from the cradle. The full line position of Fig. 2 shows the lifting ball 50 in operated or lifting position with the closed end of the bail above the hand telephone. This closed end portion forms the finger grip for enabling the user to lift and move the telephone. It should be noted that the two legs of the bail 50 curve near the pivoted open ends in such a manner that the hand telephone 60 is not displaced from the plungers 22 with the bail 50 in lifting position. This curvature of the bail 50 also allows the closed end portion or the finger grip portion to be rotated above the hand telephone at approximately a point above the center of gravity of the entire telephone.

Figs. 6 and 7 show a somewhat similar U-shaped lifting ball 70 having rounded pins 71 which are insertable in the holes 35 of the mounting blocks 32 to permit rotation of the closed end or finger grip portion above the hand telephone 60. The curvature of this bail likewise permits the rotation of the finger grip portion above the hand telephone to lifting position without displacing the hand telephone from the plungers 22. The normal position of this bail corresponds to the dotted lines in Fig. 2 while the lifting position corresponds to the full line position of bail 50 also shown in Fig. 2. Bail 70 like bail 50 also rests in the channel formed by the side walls 17 and 18 and rear surface 16 out of the way of the fingers of the user when removing the hand telephone from the cradle.

Having described the invention, what is considered to be novel is pointed out in the appended claims.

What is claimed is:

1. In a desk telephone, a casing having a cradle support for the hand telephone, a fingers lifting

ball pivotally mounted in the cradle support directly below the hand telephone and above the approximate center of gravity of the entire desk telephone, the finger grip portion of said ball manually rotatable directly above the hand telephone to provide a finger grip for the user at a point above the hand telephone and approximate center of gravity, said ball having a curvature near its pivoted point such as to obviate displacement of the hand telephone during the lifting and moving of the entire desk telephone by the user.

2. In a desk telephone, a casing having inwardly and upwardly sloping front and rear surfaces and side walls, a cradle support for the hand telephone formed by the side walls, a channel below said hand telephone formed by the inside surfaces of said side walls and the rear surface, a fingers lifting bail pivotally mounted in said side walls directly below the hand telephone at a point above the approximate center of gravity of the entire desk telephone and normally resting in said channel out of the way during the removal and replacement of the hand telephone from the cradle by the user, said bail having a curvature such as to permit the portion of said bail forming the fingers grip to be rotatable directly above said hand telephone and approximate center of gravity by the user for use in lifting and moving the entire desk telephone without the necessity of removing the hand telephone from its cradle support.

3. In a desk telephone, a casing having side walls, a pair of spaced pillars terminating the upper extremities of each side wall and forming the cradle support for the hand telephone, a plunger positioned between each pair of pillars in said side walls, a fingers lifting ball rotatably mounted in said cradle support between each pair of pillars, the finger grip portion of said ball manually rotatable directly above the hand telephone to a point above the approximate center of gravity of the entire desk telephone, said ball having a curvature such as to obviate displacement of the hand telephone and operation of said plungers during the lifting and moving of the entire desk telephone by the user.

4. In a desk telephone, a cover comprising one piece having inwardly and upwardly sloping front and rear surfaces and side walls, a pair of pillars terminating the upper extremities of each side wall and forming the cradle support for the hand telephone, a channel formed by the rear surface and the inside surfaces of the side walls, a mounting block positioned between each pair of pillars forming the base portion of the cradle support, a plunger in each side wall extending through said blocks between said pillars, said plungers operable in response to the removal and replacement of said hand telephone with respect to said cradle support, a fingers lifting bail pivotally mounted in said mounting blocks and the finger grip portion of said ball rotatable in said channel to a point directly above the hand telephone and approximate center of gravity of the entire desk telephone for lifting and moving the desk telephone including the hand telephone from place to place, said bail having a curvature such as to obviate displacement of the hand telephone thereby preventing operation of said plungers during the lifting and moving of said desk telephone.

HANS SENGBUSCH.
